UNITED STATES PATENT OFFICE.

JESSE G. KEITH, OF SPOKANE, WASHINGTON, ASSIGNOR OF ONE-HALF TO AMERICAN SECURITIES COMPANY, A CORPORATION OF WASHINGTON.

SIEVE-ADJUSTER.

No. 887,480.

Specification of Letters Patent.

Patented May 12, 1908.

Application filed May 17, 1907. Serial No. 374,168.

To all whom it may concern:

Be it known that I, JESSE G. KEITH, a citizen of the United States, residing at Spokane, in the county of Spokane and State of Washington, have invented certain new and useful Improvements in Sieve-Adjusters, of which the following is a specification.

My invention relates to devices for regulating the angle of the sieves in a threshing machine and has for its object the provision of means for adjusting the sieves while the machine is in operation, if desired, the adjusting means being exterior of the threshing machine casing.

15 The construction and operation of my improved sieve adjuster will be described in detail hereinafter and illustrated in the accompanying drawings in which—

Figure 1 is a side view of a sieve shoe showing my improvements installed thereon, Fig. 2, a longitudinal sectional view, Fig. 3, a front end view, and Fig. 4, a rear end view.

In the drawings similar reference characters indicate corresponding parts throughout the several views.

A indicates the sieve shoes of a threshing machine.

1 indicates plates secured to the front end of shoes A having curved slots 2 therein.

30 3 indicates the racks for supporting one end of the sieves 4 consisting of plates as shown with combs 5 for receiving the sieves. The racks 3 are secured together by means of rods 6 having rollers 7 on their outer ends 35 mounted in slots 2.

8 indicates plates pivotally mounted on the shoes A near the delivery end thereof by means of pins 9 secured to the upper ends of said plates 8.

40 10 indicates a comb on each plate to receive the other end of the sieves.

The lower ends of plates 3 and 8 are connected by means of rods 11 so that as the racks 3 are adjusted by the mechanism hereinafter described the racks 8 are swung so as to insure the combs being equidistant apart and their teeth for supporting the sieves on the same plane so as to prevent jamming of the sieves and combs.

50 12 indicates a rock shaft, rectangular in cross-section, journaled on plates 1, 13 crank arms secured to said rock shaft, and 14 links connecting crank arms 13 and plates 3.

15 indicates an arm secured to one end of rock shaft 12 outside of shoe A, and 16 a rod 55 secured to arm 15.

17 indicates a rack on rod 16, 18 a catch to engage the teeth of said rack and 19 leaf-springs bearing against the rod 16 to hold rack 17 and catch 18 in engagement. 60

20 indicates a cross-rod connecting the pivoted plates 8.

It will be understood from the above description and the drawings that by moving rod 16 the rock shaft 12 is rotated and 65 through crank arms 13 and links 14 the racks 3 are raised or lowered as desired so as to arrange the screens supported by the racks in position for the most effectual operation.

Having thus described my invention what 70 I claim is—

1. In combination with sieve shoes, racks for holding the front and rear ends of the sieves, the racks at one end of the sieves being slidably mounted on the shoes, the racks 75 at the other end of the sieves being pivotally secured to the shoes, and operative connections between the slidable racks and the pivoted racks to secure simultaneous adjustment of the racks, substantially as shown 80 and described.

2. In combination with sieve shoes, slotted plates secured to the front end thereof, sieve racks pivotally secured to said shoes adjacent to the rear or delivery end thereof, other 85 racks slidably mounted in the slots in said plates, and rods connecting said racks to secure simultaneous adjustment thereof, substantially as shown and described.

3. In combination with sieve shoes, plates 90 secured to the front end thereof and having curved slots therein, sieve racks pivotally secured to said shoes adjacent to the rear or delivery end thereof, other racks slidably mounted in said curved slots, and rods connecting said racks to secure the simultaneous adjustment thereof, substantially as shown and described.

4. In combination with sieve shoes, slotted plates secured to the front end thereof, sieve 100 racks slidably mounted thereon, a rock shaft journaled in said plates, crank arms secured to said shaft, links connecting said arms and the racks, means to rock said shaft, other racks pivotally secured to the shoes adjacent 105 to the rear end thereof, and rods connecting

the slideable racks and the pivotally mounted racks in pairs, substantially as shown and described.

5. In combination with sieve shoes, plates secured to the front end thereof and having curved slots therein, sieve racks pivotally secured to said shoes adjacent to the rear end thereof, a cross rod connecting said pivoted racks, other sieve racks, cross rods connecting said racks, rollers on the ends of said rods and mounted in the curved slot in the plates, rods connecting each one of the slideable racks with one of the pivoted racks, a rock shaft

15 journaled in said plates, crank arms secured to said shaft, links connecting the crank arms and the plates, an operating arm secured to said shaft, and an operating rod secured to said operating arm, substantially as shown and described.

20 In testimony whereof I hereto affix my signature in the presence of two witnesses.

JESSE G. KEITH.

Witnesses:

GEORGE R. LOVEJOY,
ROBT. L. McWILLIAMS.
